UNITED STATES PATENT OFFICE.

CARL R. DAELLENBACH, OF BRADDOCK, PENNSYLVANIA.

INTERNAL-COMBUSTION ENGINE.

No. 866,002.

Specification of Letters Patent.

Patented Sept. 17, 1907.

Application filed November 21, 1905. Serial No. 288,396.

To all whom it may concern:

Be it known that I, CARL R. DAELLENBACH, a citizen of the United States, residing at Braddock, in the county of Allegheny and State of Pennsylvania, have 5 invented new and useful Improvements in Internal-Combustion Engines, of which the following is a specification.

My invention pertains to internal combustion engines; and it has for one of its objects to provide a simple and compact internal combustion engine designed more particularly to use liquid fuel and constructed with a view of supplying heated air to low grade liquid fuel so as to assure quick evaporation of such fuel and proper operation of the engine at any temperature, and this without resort to the use of piping, mixing apparatus and the like.

Another object of the invention is the provision in an internal combustion engine of simple and efficient means for regulating the speed of the engine, and:

20 Another object is the provision in an internal combustion engine of compact and efficient means through the medium of which the engine may be readily reversed when necessity demands.

Other advantageous features peculiar to my invention will be fully understood from the following description and claims when the same are considered in connection with the accompanying drawing forming part of this specification, in which:

Figure 1 is a longitudinal sectional view of the engine constituting the present and preferred embodiment of my invention with some of the parts in elevation. Fig. 2 is a detail transverse section taken through the reversing gear of the engine in the plane indicated by line 2—2 of Fig. 1.

35 Referring by letter to the said drawing: A is the casing of my novel engine which may be arranged horizontally, vertically or at an angle of inclination, as required.

B is a transverse shaft journaled in opposite side 40 walls of the casing and having a crank C movable within the same.

D is a rectilinearly movable piston connected through a pitman E with the crank C and arranged to divide the casing into a crank chamber F and an explosion chamber G; and H is a water jacket surrounding the explosion chamber G and designed to prevent undue heating thereof in the ordinary well known manner.

In addition to the crank chamber F and the explosion chamber G, the casing A is provided with a mixing chamber I, a valve chamber J, a port K intermediate the valve chamber J and the inner portion of the explosion chamber G, a port L intermediate said valve chamber J and the atmosphere, and a chamber 55 M arranged at the outer side of the head of the explosion chamber and communicating at one end with the

mixing chamber I. The chamber M is connected by ports N with the atmosphere, and the said ports N are sufficient in number and size to avoid the making of noise when air is drawn through the same and into 60 the chamber M on the outstroke of the piston D, as will hereinafter be more fully explained. The air drawn as stated into the chamber M will tend to prevent undue heating of the cylinder head and will become heated by reason of its proximity to the head 65 with the result that when it reaches the mixing chamber I it will be in a condition to accelerate evaporation of low grade liquid fuel and thereby assure proper operation of the engine at any temperature.

P is a fuel supply conduit adapted to be connected 70 with a suitable source of supply and leading to a taper bore Q which communicates at its reduced end within the chamber I. R is a taper valve which is arranged in the taper bore Q and is backed by a spring S which in turn is backed by a plug T. U is a port intermediate 75 the mixing chamber I and the valve chamber J, and W is a valve adapted to normally close the said port U and control the supply of explosive mixture to the chamber G. The said valve W is provided with a stem X, and on said stem is a plate or other abutment 80 Y between which and the casing a spring Z is interposed; said spring having for its office to normally hold the valve W against and return said valve to its seat. The abutment Y is arranged to engage the taper valve R, and hence it follows that when the 85 valve W is drawn away from its seat by the suction created on the outstroke of the piston D, the valve R will be opened against the action of the spring S with the result that liquid fuel will be drawn into the chamber I and there commingled with the heated air from 90 the chamber M.

In order that the extent to which the valve W is opened may be regulated with a view of controlling the speed of the engine, I provide the mechanism shown at the left of the drawing. This mechanism 95 comprises a head a on the outer end of the valve stem X, a washer b of leather or other suitable soft material mounted on the valve stem at the inner side of the head and designed to prevent noise when the valve W is suddenly opened or drawn away from its seat, a threaded plug c arranged in a correspondingly threaded aperture d in the casing, and a rotary and endwise movable sleeve e disposed in the said plug c. The said sleeve is engaged with the plug, preferably through the medium of a fast thread f, and hence it will be apparent that when the sleeve is turned in one direction it will be quickly moved outward or toward the head a and when it is turned in the opposite direction it will be moved at a similar rate of speed inwardly or away from the said head a. The head a or rather the washer 105 b bringing up against the outer end of the sleeve e limits the extent to which the valve W opens, and

hence it will be apparent that when the distance between the head *a* and the sleeve *e* is diminished by outward adjustment of the said sleeve the speed of the engine will be reduced in a greater or less degree, while 5 when the distance between the outer end of sleeve *e* and the head *a* is increased by inward adjustment of the sleeve the speed of the engine will be correspondingly increased. The sleeve *e* may be turned by hand through the medium of a lever *g* or other suitable 10 means, or if preferred said sleeve may be connected with and moved through the medium of suitable governor mechanism deriving motion from the crank shaft *B* or any other suitable working part of the engine.

15 By reason of the taper valve *R* being opened by the abutment *Y* on the stem of the valve *W*, the opening of the said valve *R* always corresponds in extent to the opening of the valve *W* which assures the supply of a proper quantity of liquid fuel to the heated air in the 20 chamber *I* and a proper explosive mixture at all speeds.

A' is a valve arranged to control the exhaust port *L* and having a stem *h* guided in the casing *A* and terminating in a threaded portion *i*.

25 *B'* is a rod guided in a chamber *j* of the casing and having a tubular portion *K*² and also having a threaded bore *l* receiving and engaging the threaded end of the valve stem.

C' is an anti-friction roller carried on the end of the rod *B'*.

30 *D'* is a coiled spring arranged in the chamber *j* and the tubular portion of the rod *B'* and interposed between the casing *A* and said rod so as to return the valve *A'* to and normally hold the same against its seat; and *E'* is a set screw which bears in the rod *B'* 35 and against the threaded end of the valve stem so as to prevent casual movement of the one with respect to the other, and is disposed and movable in a longitudinal guideway *F'*, this latter in order to hold the valve stem and the rod *B'* against turning on their axes and thereby 40 assure the anti-friction roller *C'* always being in proper position to be engaged by the cam presently described.

45 *G'* is an endwise movable shaft mounted in opposite side walls of the crank chamber *F* at about the distance shown from the crank shaft *B*.

50 *H'* is a cam fast on the shaft *G'* and having an arm *I'* carrying a lateral tapered plug *J'*. *K'* is a spur gear through which the shaft *G'* is adapted to be moved endwise for a purpose presently set forth; said gear *K'* having tapered sockets *L'* arranged about the proportional distance illustrated apart, one of said sockets being shown in Fig. 1 and the other in Fig. 2, and also having lateral abutments *M'* in close proximity to the sockets *L'*, and *N'* and *P'* are gear wheels which in connection with the gear wheel *K'* are adapted to reduce the speed of the crank shaft *B* from two to one—that is to say, to assure the crank shaft turning through two complete revolutions while the shaft *G'* is turning through one revolution.

60 In the practical operation of my novel engine, it will be observed that on the outstroke of the piston *D* the suction created in the chamber *G* will operate to open the valve *W* and the taper valve *R*, and draw atmospheric air through the chamber *M* into the mixing chamber *I*, and also draw a charge of explosive mixture

from the said chamber *I* into the explosion chamber *G*. On the inward stroke of the piston *D* the said charge will be compressed until the crank *G* passes the dead center when the charge will be ignited and the piston forced outwardly to repeat the operation before stated. 70 At the proper time subsequent to the explosion of the charge of explosive mixture the cam *H'* operating against the anti-friction roller *C'* will open the valve *A'* and assure the proper discharge of the products of combustion from the chamber *G*. 75

With the cam *H'* arranged as shown, relative to the spur gear *K'*, it will be observed that the engine will run forward. When, however, the shaft *G'* is moved endwise, by hand or through the medium of any suitable mechanism, it will be observed that the taper plug *J'* will be withdrawn from the taper socket *L'* in which it is shown as resting. The shaft *G'* may then be turned to carry the taper plug *J'* into alignment with the other socket *L'*, after which the shaft is moved endwise in the opposite direction to that first mentioned so as to position the plug in the latter socket *L'* and the arm *I'* against the abutment *M'* adjacent to the said socket. With the cam *H'* thus positioned, relative to the wheel *K'* and the anti-friction roller *C'*, the engine will obviously run in a reverse 80 direction or backward.

When the cam *H'* is turned in the manner and for the purpose stated, the abutments *M'* will preclude the plug *J'* moving past the sockets *L'*, and in that way will assure quick engagement of the plug with the gear *K'*. 95

In addition to the features hereinbefore described, the casing *A* is provided with a drain aperture *A*² leading from the mixing chamber *I*. This aperture *A*² has for its purpose to drain the said chamber *I* of liquid fuel, this in order to prevent accumulation of liquid 100 fuel in the chamber *I* and interference with the starting of the engine.

The chamber *I* is, by preference, formed in a bushing disposed in the casing *A* as illustrated.

The openings *a'* and *b'* in communication with the valve chamber *J* are for the reception of the members of an igniting mechanism which *per se* forms no part of my present invention. The said members which are lettered *c'* and *d'* are designed to be electrically connected with a source of electric energy not shown. I 110 desire it distinctly understood, however, that I merely illustrate the members *c'* and *d'* in order to complete the engine, and that any other igniting means may be employed without involving a departure from the scope of my invention. 115

Having described my invention, what I claim and desire to secure by Letters-Patent, is:

1. In an internal combustion engine, the combination of a piston, a casing containing the piston and having an explosion chamber, a mixing chamber, a conduit tapered in a direction away from the explosion chamber and communicating at its reduced end with the mixing chamber and arranged to be connected with a source of fuel supply, a conduit for supplying the mixing chamber with air, a valve arranged to control communication between the mixing chamber and the explosion chamber and having a stem and also having an abutment on said stem, a spring interposed between the casing and said abutment and arranged to yieldingly hold the valve to its seat, a spring-pressed valve movable in the taper bore, parallel to the 120 stem of the first mentioned valve, and tapered in a direction away from the explosion chamber and having its outer end arranged to be directly engaged by the abutment 125

- on the stem of said first mentioned valve, a threaded sleeve surrounding the stem of the first mentioned valve and arranged in and engaging a correspondingly threaded bore in the casting; said sleeve being adjustable in the direction of its length, and a head on the outer end of the valve stem.
2. In an internal combustion engine, a piston, in combination with a casing containing the piston and having an explosion chamber, a mixing chamber, a conduit tapered in a direction away from the explosion chamber and communicating at its reduced end with the mixing chamber and arranged to be connected with a source of fuel supply, a conduit for supplying the mixing chamber with air, a valve arranged to control communication between the mixing chamber and the explosion chamber and having a stem and also having an abutment on said stem, a spring interposed between the casing and said abutment and arranged to yieldingly hold the valve to its seat; a spring-pressed valve mov- 10
able in the taper bore, parallel to the stem of the first mentioned valve, and tapered in a direction away from the explosion chamber and having its outer end arranged to be directly engaged by the abutment on the stem of said first mentioned valve, a threaded plug in the casing, a threaded sleeve surrounding the stem of the first mentioned valve and engaging a correspondingly threaded bore in the plug; said sleeve being adjustable in the direction of its length, a head on the outer end of the valve stem, and a washer arranged at the inner side of said head and adapted to bring up against the adjustable sleeve. 20
25
- In testimony whereof I have hereunto set my hand in presence of two subscribing witnesses.
- CARL R. DAELLENBACH.
